INVENTOR

Edward Gerrard,
BY
Chester Bradford,
ATTORNEY

UNITED STATES PATENT OFFICE.

EDWARD GERRARD, OF INDIANAPOLIS, INDIANA, ASSIGNOR TO THE NATIONAL DRY KILN COMPANY, OF INDIANAPOLIS, INDIANA, A CORPORATION OF INDIANA.

DRY-KILN.

SPECIFICATION forming part of Letters Patent No. 699,839, dated May 13, 1902.

Application filed April 3, 1901. Serial No. 54,111. (No model.)

To all whom it may concern:

Be it known that I, EDWARD GERRARD, a citizen of the United States, residing at Indianapolis, in the county of Marion and State 5 of Indiana, have invented certain new and useful Improvements in Dry-Kilns, of which the following is a specification.

My said invention relates to that class of dry-kilns commonly employed in the drying 10 or seasoning of lumber and is an example of what is known as the "moist-air" type of kilns.

The object of my said invention is to provide a kiln in which the moist and heated air 15 will thoroughly circulate among the pieces of lumber or other articles to be dried and be utilized to the utmost extent before escaping from the kiln, as will hereinafter be more particularly described and claimed.

Referring to the accompanying drawings, which are made a part hereof and on which corresponding reference characters indicate similar parts, Figure 1 is a perspective view 20 of a dry-kiln embodying my said invention; Fig. 2, a longitudinal sectional view, on a somewhat-enlarged scale, showing the arrangement of the openings into the flues through which the air and moisture escape 25 from the kiln and the adjustable covers or doors by which they are regulated more plainly; Fig. 3, a horizontal sectional view as seen from the dotted line 33 in Fig. 2, and Fig. 4 a horizontal sectional view as seen from the dotted line 44.

In my improved kiln the floor 1 contains a suitable slatted portion 2, up through which the air enters the kiln, said air being heated by any suitable system of heating-pipes (not shown) or otherwise. This slatted portion of 35 the floor is near the end of the kiln under the pipes of the heating system, and the air consequently is compelled to travel nearly the whole length of the kiln among said pipes before reaching the flues 3, and consequently 40 will pass around and among the lumber being dried and will be held within the kiln until it reaches said flues (which are at the extreme end) and is thus utilized to the greatest possible extent. In other words, every 45 heat unit radiating from the heating appara-

tus must travel the full length of the kiln, thus insuring a complete performance of its work and avoiding the unevenness of the operation which results when the heated and moisture-laden air is diverted at other points. 55

The escape-flues 3 at the discharge end of the kiln have widened or extended lower ends, the back sides whereof run in an inclined direction from the bottom toward the top of the interior of the kiln, as shown, and 60 the openings leading thereto, through which the air escapes after having done its work, are positioned near this inclined side or wall of said flues. This arrangement insures a substantial equal draft at all heights from 65 the floor, the lower ingress-opening being enough farther within the kiln to make it substantially equal in drawing power to those above, which are progressively nearer the end of the kiln, as shown. The exact regulation 70 of the draft is obtained by means of the sliding doors 4, covering these ingress-openings, and these may be manipulated as desired by means of rods or handles 5, connecting with said doors and extending to within easy reach 75 of the operator.

The side walls 6 of the kiln, as well as its roof 7, are usually formed solid and at the ends have the vertical moving gates or doors 8 and 9, which are substantially the full size 80 of the ends of the kiln, so that cars carrying the lumber may be run in or withdrawn to the entire capacity of the kiln. These doors are hung on ropes, as 10, and counterbalanced.

In operation when the car of lumber is first 85 inserted into the kiln it is at once enveloped in the moist heat, which prevents the stock from case-hardening, warping, and checking. As the lumber leaves the sweating process it generally passes into a drier atmosphere and 90 higher temperature, where the drying is completed. When the kiln is once charged and regulated to suit the stock being dried, the process is simple and continuous, it being only necessary to load and discharge the kiln 95 and keep up the heat.

Having thus fully described my said invention, what I claim as new, and desire to secure by Letters Patent, is—

1. A dry-kiln having a suitable floor, walls 100

and roof, with doors at the ends said floor having suitable openings near one end for the admission of air, and escape-flues at the other end having widened lower ends, one side of 5 said flues being inclined, and the exposed side extending at right angles therewith being provided with a series of closable ingress-openings arranged parallel to the inclined edge, substantially as set forth.

10 2. The combination, with a dry-kiln, of escape-flues therefor located at one end thereof, said flues having inclined rear edges and a series of adjustable closable ingress-openings near to and at equal distances from said inclined rear edges, substantially as and for the 15 purposes set forth.

3. The combination, in a dry-kiln, of the body thereof, flues therein having widened lower ends provided with ingress-openings equidistant from the inclined side thereof, 20 doors to said openings, and handles to said doors extending to a convenient point for the operator, substantially as shown and described.

In witness whereof I have hereunto set my 25 hand and seal at Indianapolis, Indiana, this 28th day of March, A. D. 1901.

EDWARD GERRARD. [L. S.]
